UNITED STATES PATENT OFFICE.

JOHN C. KIRK, OF SAN FRANCISCO, CALIFORNIA.

DISPENSING DEVICE.

Application filed January 4, 1921. Serial No. 435,042.

To all whom it may concern:

Be it known that I, JOHN C. KIRK, a citizen of the United States, and a resident of the city and county of San Francisco, State of California, have invented a new and useful Dispensing Device, of which the following is a specification.

This invention relates to a device for facilitating the discharge of granular or powdery material from a hopper or container.

It is an object of the present invention to provide a dispensing device in which granular or powdery material may be maintained in storage for convenient access, and to provide for the ready discharge of such quantities of the material, as may be desired, by the opening of a suitable closure or shutter at the discharge mouth of the container.

It is, in this connection, a further object of the invention to provide a self-closing shutter adapted for the application of pressure to interposed lumps of the material so that the lumps will be crushed or cut and the shutter enabled to snugly close.

A further object of the invention is to provide means in the form of an agitating or breaking device arranged within the container or hopper operable so as to cut or break up the material in case it has hardened or become lumpy. Further, it is an object to provide means for operating the breaker or agitator and preferably to provide an operating device having the dual function of actuating the shutter and for manipulating or actuating the agitator.

Another object of the present invention is to provide a construction involving a container or hopper having a discharge mouth upon which there is movably mounted a discharge nozzle in which there is arranged a shutter.

It is an important object of the present invention to provide an extremely simple, practicable, substantial and easily operable dispensing device and to that end a feature is the utilization of means for connecting the nozzle to the hopper body having the dual function of forming the connecting element and also of forming the agitating or breaking instrumentality.

The invention possesses other objects and features of advantage, some of which, with the foregoing, will be made manifest in the following description of the preferred form

of the invention which is illustrated in the drawings accompanying and forming part of the present specification. It is to be understood that it is not intended to limit the invention to the embodiment shown by the said drawings and description, as variations may be adopted within the scope of the invention as set forth in the claims.

Referring to the drawings:

Fig. 1 is a perspective of the improved device illustrated in its mounted position with the cover open.

Fig. 2 is a central vertical section from front to the back of the device.

Fig. 3 is a horizontal section on line 3-3 of Fig. 2.

Fig. 4 is a detail section of the nozzle joint.

The present invention embodies a container or hopper of suitable size and shape represented in the present case as having an oblong upper body portion 2 with a cover 3 hinged to lift upwardly, and a convergent downwardly extending portion terminating in a mouth-piece 4. The mouth-piece 4 is shown as substantially in the form of a truncated hollow cone with a circular seat 5 having an inner annular recess 6 in which there is telescoped the upper end of a spout or nozzle section 7 which also may be of conical form. This nozzle section may be provided with an annular shoulder 8 to bear up against the seat or end 5 of the mouth-piece 4.

The nozzle may have its lower portion formed cylindrical as at 9, and within the same there is provided a shutter or closure in the form of a disc 10 secured upon a transversely extending shaft 11 turnable to move the shutter 10 to an open position. Preferably, the shutter is turned to a closed position automatically thru the instrumentality of a spring 12 coiled about one extended portion of the shaft and having one end connected at 13 to the nozzle and the other end connected conveniently as at 14, to a hand wheel or other manually operable device 15. The opposite end of the shaft 11 passes thru a bearing 16 having a cut away portion in its end forming a slot in which plays a stop pin 17, limiting the turning movement of shaft 11 toward an open position or toward the closed position.

To secure a simple and inexpensive form of connection of the nozzle member or section 7 to the hopper body there is provided

in the upper portion of the hopper 2 a transverse bridge or bracket 20 having a central perforated portion 21 thru which passes the cylindrical stem 22 of a rod 23 the upper 5 end of which is threaded to take nuts 24 serving to hold the rod 23 up in operative position against the bearing part 21. The lower end of the rod 23 is mounted on a cross pin 25, one end of which may be 10 screwed at 26 into the nozzle wall 7. Lateral play of the lower end of the rod 23 on the pin 25 may be prevented as by side stops or keys 27 passing thru the pin. From this it will be seen that the rod 23 forms 15 a link rotative about its own axis in the bearing 21 when the nozzle 7 is rotated about its own axis by means of the handle 15 in the shaft 11; this for the purpose of loosening the material in the hopper 2. To 20 secure this breaking up and agitation of the material, suitable breakers or radial pins 28 extend from the central link or rod 23; the lengths of the agitating or breaking pins 28 being determined by the proximity of the 25 downwardly convergent lower portion of the hopper 2.

It will be seen from the above that the 30 device is constructed of a comparatively small number of extremely simple and inexpensive elements that can be readily assembled or disconnected for cleaning, compact packing or transportation purposes.

Should any of the lumps of the material 35 being discharged from the nozzle 7 become interposed between the edge of the shutter 10 and the surrounding wall of the portion 9, pressure of the spring 12, tending to close the shutter, will serve to cut or break the lumps and therefore insure the full closure 40 of the shutter and prevent draining or wasting of the finer particles from the container.

What is claimed is:

1. A dispensing device comprising a hopper having a downwardly convergent discharge mouth, a nozzle coaxial with said mouth, means for rotatively connecting said nozzle to the mouth and for breaking clods 45

of material to be dispensed from the container, and a shutter in the nozzle for controlling the discharge of material, the shutter having a shaft forming means by which the nozzle and its connecting means may be rotated to break clods. 50

2. A hopper having a contracted discharge mouth, a nozzle rotatively mounted on the mouth, an agitator connecting said nozzle to the body of the hopper, a shutter in said nozzle, and a handle forming the shaft of the shutter and by which the nozzle may be rotated to actuate the agitator to 55 break clods. 60

3. A hopper having a contracted discharge mouth, a nozzle rotatively mounted on the mouth, an agitator connecting said nozzle to the body of the hopper, a shutter 65 in said nozzle, and a handle forming the shaft of the shutter and by which the nozzle may be rotated to actuate the agitator to break clods, the shutter being operative independently at any position of the nozzle. 70

4. A hopper having a contracted discharge mouth, a nozzle mounted to rotate on said mouth, a rod connecting the nozzle to the hopper and having clod breaking means, and a shutter in the nozzle. 75

5. A hopper having a contracted discharge mouth, a nozzle mounted to rotate on said mouth, a rod connecting the nozzle to the hopper and having clod breaking means, a shutter in the nozzle, and means for operating the shutter and turning the nozzle concurrently. 80

6. A hopper having a contracted discharge mouth, a nozzle mounted to rotate on said mouth, a rod connecting the nozzle to the hopper and having clod breaking means, a shutter in the nozzle, and means for operating the shutter and turning the nozzle concurrently or independently at any 85 position of the nozzle. 90

In testimony whereof, I have hereunto set my hand.

JOHN C. KIRK.
